ATTORNEYS

UNITED STATES PATENT OFFICE.

BENJAMIN EDWARDS, OF NEW YORK, N. Y.

LATCH.

SPECIFICATION forming part of Letters Patent No. 463,031, dated November 10, 1891.

Application filed January 7, 1891. Serial No. 376,979. (No model.)

To all whom it may concern:

Be it known that I, BENJAMIN EDWARDS, of New York city, in the county and State of New York, have invented a new and useful Improvement in Latches, of which the following is a full, clear, and exact description.

My invention relates to latches, and has for its object to provide a device of simple, durable, and economic construction, comprising but few parts, which will operate with a minimum of friction; and the invention consists in the novel construction and combination of the several parts, as will be hereinafter fully set forth, and pointed out in the claims.

Reference is to be had to the accompanying drawings, forming a part of this specification, in which similar figures and letters of reference indicate corresponding parts in all the views.

Figure 1 is a plan view of the latch with the cover of the casing removed. Fig. 2 is a longitudinal section through the complete latch, and Fig. 3 is a transverse section taken on the line 3 3 of Fig. 2. Fig. 4 is a partial plan view of the latch with the cover of the casing and the bolt removed. Fig. 5 is a detail perspective view of the guide-block viewed from the under side. Fig. 6 is a perspective view of the bolt viewed from the under side. Fig. 7 is a longitudinal section through the striking-plate employed in connection with the latch. Fig. 8 is a bottom plan view of the striking-plate, and Fig. 9 is a detail perspective view of the follower of the latch.

The casing is circular in cross-section, and comprises two longitudinal semicircular members 10 and 11, the member 10 having an end plate 12 and a front plate 13 attached, the latter being circular and of greater diameter than the body of the casing, and also provided with the usual opening for the passage of the bolt-head. All of the operative portions of the latch are preferably located in the casing member 10, the other members serving as a cover only. The rear portion of the member 10 is made solid, and the forward and larger portion is in shell form, creating thereby a longitudinal chamber A. Upon the front face of the solid portion of the casing member 11 a transverse rib 14 is produced of less length than the width of the

member, the rear face whereof is circularly concave, and the ends at said face are rounded off or convexed, as illustrated at a in Fig. 4. 55 Immediately in front of the concave surface or recess of the rib a semispherical socket or opening 15 is made, merging at the bottom into a circular aperture 16, extending through the casing, as shown in Figs. 2 and 3. Between the back plate 12 of the casing and the opening 15 the upper face of the solid portion of the member 10 is flush with the side edges of the latter, and in the central portion of this section of the solid surface a 65 longitudinal recess 17 is located, extending to the back plate and preferably upon the extreme rear bottom surface of said recess a stud 17^a is erected, one face whereof bears against the back plate 12, and said stud is 70 provided with a threaded aperture. In the socket 15 a semi-spherical follower 18 is loosely fitted, provided with a cam projection or lug 19 in its upper face, of semicircular shape, and having convexed or cylindrical 75 ends, and also provided with a rectangular or polygonal opening 20, extending through from face to face to receive a spindle, and the cam-lug 19 has an annular recess in its inner edge at the center, the walls whereof are in the same 80 vertical plane with the two adjoining walls of the follower-opening 20, as shown in Fig. 9. Normally the cam of the follower is located in the recess of the rib 14, and when in this position the convexed end surfaces of the rib 85 constitute a continuation of the curve upon which the ends of the cam are formed, as shown in Fig. 4. A guide-block 21 is fitted in the recess 17, having a slot b at its rear end to receive the stud 17^a, and a concavity 90 b' in its outer end. The block is of sufficient length to extend a slight distance over the follower, serving to hold it in position, but does not engage with the follower, being to that end provided with a recess b² in its under face at its forward end, as shown in Figs. 2 and 5. The block is held rigidly in position by a screw or an equivalent device.

The bolt B consists of a body-section 22, having a flat under face and an essentially 100 convexed upper face, and a head 23, which projects below the under face of the body. In the rear end of the body an elongated opening 24 is produced, and flush with each

- side wall of the opening, at the rear thereof, lugs 25 are formed upon the under face, the forward ends b^3 of which are curved from the opening outward, as is best shown in Fig. 6.
- 5 When the bolt is placed in position, the lugs 25 slide in engagement with the sides of the block 21, whereby the block serves not only as a keeper for the follower, but as a guide for the bolt, and it further serves as a stop 10 limiting the inward throw of the bolt. The bolt is normally forced out through the opening in the front plate of the casing by a spring C, located in the chamber A. The casing member 11 is provided with an opening 26, 15 through which the spindle operating the latch extends after passing through the follower.
- In connection with the latch I employ a striking-plate D, of peculiar construction, (illustrated in Figs. 7 and 8,) and consisting of 20 a face-section comprising a circular plate 28, and a tongue 29, extending therefrom in a plane with its outer surface, the circular plate being provided with an opening 30, which is surrounded or partly surrounded by a well 25 31, formed upon the back of the circular plate, and the striking-plate is secured in position by passing a screw through an aperture 32 in the bottom of the well into any proper support.
- 30 If in practice it be found desirable, a flange may be formed at the upper exterior surface of the follower to rest upon a wear-plate 33 of harder metal than that of which the solid portion of the casing is constructed—as, for 35 instance the casing may be made of sheet metal, and the solid portion in the member 10 may be made of lead.
- In the operation of drawing back the bolt the follower may be turned either to the right 40 or to the left by means of the spindle. In either event one of the round ends of the follower-cam will engage with the round forward corner of one of the bolt-lugs 25, and the bolt will be carried backward and the 45 cam is forced rearward until the cam strikes against one forward edge of the guide-block 21. This is the limit of the inward throw of the bolt, and its head is at this time practi-

cally within the opening of the front plate of the casing. The moment the spindle is released the spring C acts, and the cam returns to its normal position against the rib 14, and the beveled or curved ends of the bolt-flanges 25 engage with the curved ends of the said rib and the follower-cam. These two surfaces act as stops to limit the outward thrust of the bolt. By constructing the striking-plate in the manner described the fastening devices of the said plate are rendered invisible, or practically so.

Having thus described my invention, I claim as new and desire to secure by Letters Patent—

1. In a latch, the combination, with a casing and a spring-pressed bolt having lugs formed at each side, of a follower provided with a cam projection and a guide-block secured in the casing and projecting partially over the follower, whereby the follower will be held in place and the bolt guided in the casing, substantially as described.
2. In a latch, the combination, with a casing provided with a transverse rib having a concave end, and a spring-pressed bolt having lugs projecting from its under face, of a follower provided with a cam projection resting normally in the concavity of the transverse rib, and a guide-block secured in the casing and projecting partially over the follower, substantially as herein shown and described.
3. A latch comprising a sectional casing, one end of one of the sections being solid and provided with a rib having a concave end, a bolt having lugs projecting from its under face, a spring in the section of the casing having the solid portion and engaging said solid portion and the bolt, a follower provided with a cam projection resting normally in the concavity of the transverse rib, and a guide-block projecting partially over the follower, substantially as herein shown and described.

BENJAMIN EDWARDS.
